UNITED STATES PATENT OFFICE.

JAMES HASLAM, OF BURY ROAD, TONGE, NEAR BOLTON, COUNTY OF LANCASTER, ENGLAND.

CHEMICAL FIRE-EXTINGUISHING APPARATUS.

SPECIFICATION forming part of Letters Patent No. 409,038, dated August 13, 1889.

Application filed May 15, 1889. Serial No. 310,864. (No model.) Patented in England December 20, 1887, No. 17,487; in France September 21, 1888, No. 193,120, and in Belgium September 22, 1888, No. 83,353.

To all whom it may concern:

Be it known that I, JAMES HASLAM, chemical fire-engine manufacturer, of Bury Road, Tonge, near Bolton, in the county of Lancaster, England, have invented new and useful Improvements in Chemical Fire-Extinguishing Apparatus, (for which I have obtained patents in Great Britain, No. 17,487, December 20, 1887; France, No. 193,120, September 21, 1888, and Belgium, No. 83,350, September 22, 1888,) of which the following is a specification.

This invention relates to improvements in what are known as "chemical fire-extinguishers," in which a vessel containing water in solution with a carbonate or alkaline compound and a bottle containing acid are employed; and it consists in providing means for effectually and readily charging the apparatus and 20 breaking the said bottle, so as to mix the acid with the water.

Figure 1 is a sectional elevation of the upper part of my improved chemical fire-extinguisher. Fig. 2 is a side view of Fig. 1; 25 and Fig. 3 is a sectional plan through line E' F' in Fig. 1, showing segmental ribs.

A is the case of the extinguisher, to which is secured the nozzle B, provided with the elongated end O, to operate against the ring Z in the metallic ring U, attached to the swiveling lid or cover D. The outside of the nozzle B is provided with the segmental ribs T. The swiveling lid or cover D is fitted with the ring U, provided with the recess or cavity X 30 to receive the ring Z. The ring U is secured to the lid or cover D by the screwed stem Y'

and nut K². The lower end of the lid or cover D is provided with the segmental ribs V, by which the same is securely fastened when swiveled under the segmental ribs T on the 40 nozzle B. The segmental ribs T are tapered, as shown in Fig. 2, so that when the ribs V on the lid or cover D are swiveled under the same an increased pressure is imparted to the joint-ring Z. Immediately pressure is 45 imparted to the joint-ring Z it becomes stationary along with the ring U, the latter allowing the lid or cover D to swivel round its outer surface. In the ring Z is mounted the spindle G, carrying the disk H, for the purpose of 50 breaking the bottle E by striking the knob J on the spindle or stem G.

What I claim as my invention, and desire to secure by Letters Patent, is—

A chemical fire-extinguisher consisting of 55 an alkali-vessel containing an acid-bottle and having a nozzle at its top provided with lateral ribs, a swiveled cover having a central orifice and provided with ribs to engage the ribs on the nozzle, a metallic ring having a 60 cavity, and a tubular stem rising through the orifice in the cover, a joint-ring arranged in said cavity and resting on the nozzle, and a spindle extending through the tubular stem and the joint-ring and having a disk below 65 the latter, substantially as described.

In testimony whereof I affix my signature in presence of two witnesses.

JAMES HASLAM.
